UNITED STATES PATENT OFFICE.

LAWRENCE A. SUBERS, OF CLEVELAND, OHIO.

AUTOMATIC MACHINE FOR CONSTRUCTING A LAMINATED COHESIVE INTERWOUND TUBULAR FABRIC CAPABLE OF ASSUMING AN ANNULAR FORM.

1,132,635.

Specification of Letters Patent. Patented Mar. 23, 1915.

Application filed May 1, 1914. Serial No. 835,606.

To all whom it may concern:

Be it known that I, LAWRENCE A. SUBERS, a citizen of the United States, and resident of Cleveland, in the county of Cuyahoga and State of Ohio, have invented certain new and useful improvements in automatic machines for constructing a laminated cohesive interwound tubular fabric capable of assuming an annular form, of which I hereby declare the following to be a full, clear, and exact description, such as will enable others skilled in the art to which it appertains to make and use the same.

The objects of the invention are to provide an automatically acting machine for constructing a tubular fabric in annular form whereby it can be continuously made in such form as to be adaptable for use in constructing a pneumatic tire or casing 20 without distortion of the component fabric elements therein.

The machine is particularly designed for the continuous construction of a laminated, cohesive, interwound fabric in a tubular, 25 annular form upon a mandrel.

The tubular fabric is cut through or split at one side while still upon the mandrel and hence can be readily opened up and withdrawn therefrom and wound upon an oval 30 shaped roller, and the endless fabric thus obtained can be produced continuously and of indefinite length and when removed from the roller will readily reassume its tubular, annular form without distortion or 35 alteration of tension in its parts. In this condition it is ready for use, when cut to the proper length for constructing a pneumatic tire or casing.

The invention comprises a mandrel continuously movable in one direction and arranged to form a curved portion upon which the fabric is interwound and laminated in annular, tubular form. The preferred form of construction shows an endless mandrel composed of segmental shaped sections of circular cross section hinged together, the mandrel having portions which are curved in the form of the arc which corresponds in diameter with the internal diameter of the finished tire or casing desired, the circumference of the mandrel segments being equal to the requisite width of

fabric, and a fixed guiding and supporting means for the mandrel.

The invention includes reels provided with spools upon which the fabric bands are stored, and which alternately rotate in opposite directions about the mandrel, and further includes inclined supporting and guiding devices for the fabric bands, which conduct the bands to their respective positions upon the mandrel.

It also includes spools upon the reels for anwinding and storing strips of practically non-adhesive material which are wound between the layers of the adhesive fabric bands. These inclined guiding devices are each spaced about a curved portion of the mandrel and rotate at right angles to the axis thereof, and each rotates in a plane which passes through the center of curvature of the mandrel. These guiding devices are rotated in unison with their respective reels and in the same direction.

By means of separate rotating reels and separate rotating band guiding devices it is made possible to wind the bands directly upon the curved mandrel and produce a fabric of a size and shape which can be utilized in a tire or casing.

Since the mandrel is continuous it is necessary to cut the fabric longitudinally as fast as it is produced upon the mandrel. The invention therefore includes means for cutting the fabric and for winding and storing the cut fabric to prepare it for use.

The invention includes means for rotating the reels and band guiding devices, for propelling the mandrel at a predetermined rate of speed relative to the speeds of rotation of the reels, which governs the angle at which the fabric bands are interwound in forming the fabric, and also includes guiding devices, and devices for cutting and storing the fabric.

It also includes a rotatable guide ring in each band guiding device and radially moving arms which lead the bands to their respective positions in forming the fabric.

It also includes means for taking up the slack in certain bands as the guiding arm moves radially in and out in the guide holding ring.

The invention further includes the forms

of construction and combination and arrangement of parts and construction of the various details hereinafter described, shown in the accompanying drawings, and specifically pointed out in the claims.

In the accompanying drawings Figure 1 is a plan view of the entire machine; Fig. 2 is a side elevation of the same; Fig. 3 is a central longitudinal section of the machine 10 through the reel supporting standards, the mandrel, composed of connected segmental parts, and the operating means therefor; Fig. 4 is a side view of a portion of the mandrel with one half of one segment removed, 15 and shows the guide rail upon which the segments move, and the guiding rollers and hinged connections for the segments; Fig. 5 is a transverse section of segment of the mandrel on line $f-f$, Fig. 4; Fig. 6 is a side 20 view of one of the supports for the T rail that guides the mandrel; Fig. 7 is a section on a radial line through one of the brackets which supports rolls for guiding and directing one of the fabric bands to its requisite 25 concentric guide tube; Fig. 8 is a transverse section of the mandrel and gears for operating the same, taken on line $g-g$ Fig. 3; Fig. 9 is a longitudinal section of one of the 30 spools for holding Holland cloth and the friction operating sleeve therefor with its driving gear; Fig. 10 is a similar section of one of the fabric band storing spools, and stationary pivot support therefor; Fig. 11 is a section showing one of the spring 35 pressed arms which provide tension for the fabric bands as they are unrolled from the band storing spools; Fig. 12 is a transverse section through the concentric, rotating, tubular guides for the fabric bands and 40 shows the outside reel and spools thereon, and a portion of the bevel gear which revolves with the reel and which operates the outer one of the band laying rings; Fig. 13 is a longitudinal central section of the same; Fig. 14 is a side view of the supporting bracket for the take up device for the slack in each fabric band from the outside reel caused by variations in position of the guide 45 rollers due to the inclination of the plane in which the guide rollers upon the outer inclined guiding ring revolve; Fig. 15 is a plan view of the same; Fig. 16 is an enlarged central longitudinal section of the 50 outer ends of the concentric, rotating and guiding tubes, and intermediate stationary tubes and shows the vertical and inclined guiding rings and radially movable guide arms which conduct the bands to the mandrel; Fig. 17 is a transverse section on line 55 $b-b$ Fig. 16 showing the outer inclined ring which supports the radially movable and stationary guide arms that conduct the bands to the mandrel and also shows the cams by means of which the movable arms 60 are alternately extended, withdrawn, and

given a slight rotary movement; Fig. 18 is a plan view of one of the band guiding arms or rods and means for attaching the arm to the inclined ring shown in Fig. 17; Fig. 19 is a transverse section on line $h-h$, Fig. 17 through the outer inclined ring showing the cam slot therein and the inclines upon its bottom for rotating the movable guide arms; Fig. 20 is a transverse section of mandrel on line $j-j$, Fig. 16 showing the inner and vertical guide ring attached to the inner guide tube; Fig. 21 is a similar section of the mandrel showing the third and inner inclined guide ring and taken on line $k-k$ Fig. 16; Fig. 22 is a similar section 80 through the mandrel on line $l-l$, Fig. 16, showing the second or intermediate inclined guide ring; Fig. 23 is a side view of the roll supporting guide arm, used on the inner vertical guide ring shown in Fig. 20; Fig. 24 is a plan view of the roll supporting arms and rolls used with the guide ring shown in Fig. 22; Fig. 25 is a similar view of the roll supporting arms and rolls used with the guide ring shown in Fig. 21; Fig. 26 is a longitudinal section of the same showing the stationary plate which carries the cam slot; Fig. 27 is a transverse section on line $m-m$, Fig. 22 showing one of the inclines in the bottom of the cam groove which actuates 95 the guide arm; Fig. 28 is a plan view of the fabric slitting and winding mechanism which complete the action of the machine; Fig. 29 is a side elevation of the same.

In these views A, A, represent segmental 100 portions of a flexible mandrel, the segments being annular in form and of circular cross section. This mandrel may be arranged in many ways but the preferred form is illustrated in detail in Figs. 1, 2, 3, 4, and 5 of the drawings. Here B is a T shaped rail upon which the segmental portions move and for convenience each portion is longitudinally divided at a and the two portions are secured together by means of screws a' , a'' , and inclose the T shaped rail between them in the central opening a^2 provided for it. Pivoted within this opening are the rollers a^3 and a^4 which engage the long and short sides respectively of the cross bar of the T shaped rail and permit the segments to travel easily thereon. Bushings a^5 , a^6 of a suitable friction reducing material, such as arguto wood, engage the pivot pins a^6 , a^6 and make oiling unnecessary. This mandrel 120 passes over a portion B' of the rail which is curved so as to cause the mandrel to conform to the arc of the radius of the tire or casing desired; upon this portion the fabric bands are interwound and laminated at a predetermined angle to construct the tubular, annular fabric. The rail is provided also with straight sides B^2 , B^3 and return bends B^4 , B^5 .

The rail is mounted upon stationary 130

brackets *b*, *b*, secured to standards *C*, *C'* which support the reel guide tubes and other portions of the machine. One of these brackets is shown in Fig. 6. These brackets are so attached to the T rail *B* that no obstruction is offered to the passage of the mandrel segments *A*, *A* thereon.

The mandrel is propelled by means of a toothed wheel *D* which passes through an opening *d* in the inner edge of each segment *A*, *A*, and engages a pin *d'* transversely placed across the opening, but short enough to clear the T rail *B*.

When the segments are passing over the curved portion *B'* of the T rail where the fabric is interwound and laminated upon the mandrel the sides of the segments make contact with each other so that all openings are closed and a perfect continuous quarter of an annulus is produced, circular in cross section and of a circumference equal to the width of fabric desired, and having its outer circumference corresponding with the inner circumference of the tire or casing to be produced from the fabric constructed thereon.

To preserve continuity in the mandrel and an unbroken outer edge, the segments are hinged together at their upper edges by means of a curved arm *A*² in one segment engaging a corresponding curved recess *A*³ in the adjacent segment. The center of movement is shown in Fig. 4 to be located at the exact meeting corners of the outer edges of the segments. The toothed wheel *D* is operated by means of the bevel gears *D'*, *D*² and spur gears *D*³, *D*⁴, and *D*⁵, and is mounted upon the standard *D*⁶. A main shaft *H* supplies the necessary power.

In Figs. 1, 2, 3, 8, 12, 13, 14, 15, 16, 17, 20, 21, and 22 are shown the reels, the feeding tubes for the fabric bands, which encircle a straight portion of the mandrel, and the guiding devices which conduct the fabric bands to the curved portion of the mandrel. In these views *C*, *C*, are standards upon which the tubular stationary bearings *E*, *E* are secured by means of caps *E'*, *E'*. The tubular bearings extend upon both sides of the standards and support the reels *F*, *F'*, *F*², *F*³, respectively.

Each reel is rotated by means of a train of spur gears as shown in Figs. 1, 2, 3, 8, 12, and 13. Reels *F*', and *F*³ are rotated in the same direction upon the bearing tube *E*, *E* by the spur gears *G'*, *G*³, and *G*² operated by the gear *G* upon the shaft *H*. Reels *F* and *F*² are rotated in the same direction but by the gear *G* upon the shaft *H*. Reels *F* by means of the spur gears *G'* and *G*⁴ driven by gear *G* upon the main shaft *H*. The standards, *C*', *C*', support stationary tubes *I*, *I*', (see Fig. 3) through the inner one of which the mandrel passes, and a stationary tube *I*² is supported upon the

standard *C* which supports the reels *F* and *F*'. The concentric tubes *J*, *J'* and *J*² are respectively attached to and rotated by the reels *F*, *F*', *F*², by means of circular plates *K*, *K*, having openings *K*', *K*', therein for the passage of the fabric bands to the respective guiding tubes. At the outer ends of the tubes are attached bushing spacers *K*², *K*², bearing on the inner surface of the stationary tubes *I*², *I*', and bearing tube *E*. Through the annular spaces between the stationary and rotating tubes are passed the fabric bands *x*, *x*, openings *K*³, *K*³, being provided in the spacers *K*², *K*².

The reels are constructed as shown in Figs. 1, 2, 3, 8, 10, 12, and 13, and each carry four projecting wrists or pivot bearings *c* upon which are detachably secured two spools *c*', *c*² upon which the adhesive fabric bands *x*, *x*, are wound alternately with bands of non-adhesive material *x'* such as Holland cloth, and the spools are detachably secured upon their pivot pins by means of a simple form of spring latch *c*³ shown in Fig. 10.

The adhesive bands are guided to the openings between the guiding tubes by means of guide rollers *C*', *C*', and tension is exerted upon the bands upon the spools by means of spring pressed arms *C*⁵, *C*⁶, as seen in Figs. 8 and 12. A detail of this tension arm is shown in Fig. 11.

The spools *L*, *L*, for Holland cloth are rotated by the friction of the spring pressed key *Q* in the sleeve *Q*', driven by the spur gear *M*², mounted thereon, the pinion *M*' and the gear *M*³ mounted on the reels, and operated by the stationary gear *M* upon the reel standard. The spring catch *Q*² retains the spools upon the pivot *Q*³.

At the outer ends of the rotating guiding tubes *J*, *J'*, *J*², the mandrel and its guide rail are curved in the arc of a circle having a radius equal to the inside radius of the tire casing for which the fabric is being constructed. See Figs. 2, 3, 16, and 29. To the outer end of the rotating tubes *J'* and *J*² are respectively attached the bevel gears *f* and *f'* and to the outer reel *F*³ the bevel gear *f*³ is secured by the brackets *f*⁴, *f*⁴. To the outer ends of the stationary tubes *I*² and *I*', and bearing tube *E* are respectively attached suitably shaped tubular brackets *I*³, *I*⁴ and *I*⁵, upon whose outer extremities are respectively mounted rings *n*, *n*', and *n*², having bevel gears *N*, *N*', and *N*² which engage the gears *f*, *f'* and *f*³. These rings *n*, *n*', and *n*² are suitably spaced apart and encircle the curved portion of the mandrel and each rotates in a plane at right angles to the axis of the mandrel and passes through the center of curvature of the annulus formed by the mandrel and at a sufficient angular distance apart to permit the operation of the devices for conducting the

adhesive fabric bands to their precise positions upon the mandrel.

- To the inner rotating tube J is attached a tubular bracket I^6 upon the vertical face of which are mounted the guiding devices for the fabric bands x, x' , these guiding devices consisting of rollers P', P'_1 , and angularly positioned rollers P^2, P^2 on supports P^3, P^3 . The angular position of the rollers P^2, P^2 , is determined by the angle at which the bands are to be interwound in forming the fabric. The second ring n is provided with a bevel gear N and is operated by bevel gear f upon the tube J' , and since it is inclined to the axis of the tube J' in a plane at right angles to the axis of the mandrel and passing through the center of curvature of the latter, as it rotates about the mandrel the horizontal distance from the outer edge of the ring to the outer edge of its respective tube changes constantly. Therefore to keep the adhesive bands in horizontal position until they can enter the guides upon the ring, guide rollers R, R , are provided mounted upon radially movable arms R', R' , (see Figs. 21, 25 and 26) and rollers R^3, R^3 pivoted on the inner ends of these arms, engage a cam groove R^2 in the extremity of the tube. From the guide rollers upon the movable arms the adhesive fabric bands pass to angularly placed guide rollers R^4, R^4 upon the inner ends of stationary arms R^5, R^5 and thence to the mandrel.
- In Fig. 22 the guiding means are shown for the next reel and tube, inclined at a different angle. The construction is similar to that shown in Fig. 21 with the exception that the extremity of each moving arm is provided with an attached block r , having balls or rolls r', r' , which engage the edges of the cam groove R^2 and impart radial motion to the arm and also have pins r^2 and r^3 which engage inclines r^4 in the bottom of the cam groove so that a rocking movement is imparted to the arm R' in order that roller R may be turned to the proper angle to receive the band in its horizontal position due to the gain in lead of the roller R from the varying radii of its curved path. The pin r^2 is stationary and the pin r^3 spring pressed so as to keep both pins in contact with the inclined bottom surface of the cam groove.
- It will be seen that the axis of revolution of each arm is always at right angles to the center of the edge of each guide roller R so that the bands will not come off from the rollers R^4, R^4 .
- In Figs. 16, 17, 18, and 19 the construction of the outer gear ring having the greatest amount of inclination is shown, the construction being similar to that shown in Fig. 22 except the radial arm R' is tubular

in shape and the band passes through it to 65 the roll R^4 .

In Figs. 13, 14, and 15 is shown a device comprising a cam actuated swinging arm S by means of which the slack in the band is taken up, which occurs periodically as the 70 bands are fed to the inclined guides. The swinging arm S is mounted on the bracket f^4 and carries guide rolls S' and S^2 on its inner and outer extremity. Guide rolls S^3, S^4 , and guide roll S^5 at right angles to S^4 are mounted on bracket f^4 . The band passes over the rolls in the following manner: S^3 to S^3 to S' to S^4 to S^5 to R . The movement of the arm takes up the slack as the band passes over the roller S' on its 80 outer end. The swinging arm S is actuated by means of a camming surface S^7 on the bearing tube E , and is held in contact therewith by the spring S^8 . Radially mounted guide rollers S^6, S^6 , on tubes J', J' 85 and J^2 guide the bands to the rollers R', R' on the rings N and n' .

In Figs. 1, 2, 28 and 29 are shown the various devices for cutting the fabric longitudinally after it has been formed upon 90 the curved portion (designated at Y) of the mandrel, and for storing the fabric upon a suitable roller or spool after it has been opened up and withdrawn from the mandrel. In these views T is a circular knife 95 which slits the fabric upon the inner surface as it passes over the closely joined mandrel segments. This knife is rotated by any suitable means such as the pulley T' , shaft T^2 and belt T^3 and is mounted upon the standard T^4 . The knife cuts directly into the opening provided for the mandrel driving toothed wheel. After being cut the fabric is opened up, withdrawn from the mandrel and is wound upon the crowned 105 roller V which is of greater diameter at the center than at its ends, the inner surface of the fabric coming next the roll, and the fabric will be wrapped thereon without distortion so that when unwound from 110 the roller it will assume its tubular annular shape.

The roller may be driven by means of any desired means. In Fig. 28, V' is a sprocket gear free to rotate on shaft V^2 of the roller 115 V supported by standard V^3 and is driven by a sprocket chain V^4 and sprocket wheel V^5 mounted on shaft V^6 in standard V^7 . The bevel gear V^8 on shaft V^6 is driven by bevel gear V^9 on the main shaft H . V^{10} 120 and V^{11} are plates keyed to shaft V^2 and engage the sides of the sprocket wheel V' by pressure of the spring V^{12} thus allowing the speed of the roll V to decrease by slippage as the fabric accumulates thereon. 125 Shaft H is driven by reducing gear V^{13} mounted thereon and pinion V^{14} on shaft V^{15} in standard V^{16} carrying tight and loose

pulleys V^{17} and V^{18} respectively. V^{16} is a roller upon which a band of Holland cloth or other non-adhesive material is wound, and from which it is introduced between the windings of the cohesive interwound fabric upon the roller V .

It is obvious that the guide rolls next the mandrel may be so constructed and controlled as to have the width between their flanges automatically changed according to their angular position around said mandrel so that bands having regularly recurring wide and narrow portions may be used in constructing the annular fabric, the width 10 between the flanges of said rolls being greatest at the outer circumference of the fabric and least at the inner circumference of the same, without departing from the spirit of the invention or the scope of the 20 claims.

Having described the invention what I claim as new and desire to secure by Letters Patent is:

1. In a machine for constructing a tubular, annular fabric, in combination, a flexible mandrel curved at one portion in the form of an arc, spaced devices rotatable about said curved portion of said mandrel for winding fabric bands thereon to construct said fabric, means for propelling said mandrel through said rotatable devices, and means for rotating said band winding devices at a predetermined rate of speed relative to the rate of propulsion of 30 said mandrel.

2. In a machine for constructing tubular, annular fabric, a flexible mandrel having a curved portion, a series of band conducting devices rotatable about said curved portion 40 of said mandrel, said band conducting devices spaced apart and arranged in planes at right angles to the axis of the mandrel and in radial lines to the curvature of said mandrel, means for rotating said band conducting devices, and means for advancing the curved mandrel at a predetermined rate of speed.

3. In a machine for constructing a tubular, annular fabric, a flexible curved mandrel, a series of band conducting and applying devices rotatable about said curved mandrel, means for rotating said band conducting and applying devices, means for propelling said mandrel, means for cutting said 55 fabric on a longitudinal line, and means for removing the same from the mandrel.

4. In a machine for constructing a tubular, annular fabric, a curved mandrel, a series of spaced band conducting and applying devices, rotatable about said curved mandrel at different angles of inclination to each other, means for propelling the mandrel, means for storing said bands and for guiding them to said band conducting and applying devices, means for rotating said 60

conducting and applying devices about said mandrel.

5. In a machine for constructing a tubular, annular fabric, in combination, a longitudinally moving flexible mandrel, means 70 for curving the mandrel into the form of an arc of a circle as it passes through one portion of the machine, spaced devices rotatable about the aforesaid curved portion of the mandrel for conducting fabric elements thereto and for winding them thereupon, means for rotating said conducting and applying devices, and means for propelling said mandrel.

6. In a machine for constructing an annular, tubular fabric, in combination, a flexible mandrel, a guiding support upon which said mandrel is mounted, said guiding support having a curved portion, means for propelling said mandrel longitudinally of 80 said guiding support, devices for conducting and applying fabric bands to the curved portion of said mandrel and said devices positioned in several radii of the curve of said mandrel, means for detachably mounting said flexible mandrel upon said guiding support and for propelling said mandrel thereon, and means for rotating said band, conducting and applying devices about the curved portion of said mandrel.

7. In a machine for constructing an annular, tubular fabric, in combination, a flexible mandrel, a guiding support therefor, having a straight and a curved portion, reels and band storing spools thereon rotatable 100 about the straight portion of said mandrel and guiding support, devices actuated by said reels, and rotatable about the curved portion of said mandrel for conducting and applying said bands thereto, and means for guiding said bands from said reels and spools to said band conducting and applying devices.

8. In a machine for constructing an annular, tubular fabric, a flexible, longitudinally movable mandrel, a guiding support therefor provided with a straight and a curved portion, reels rotatable about the straight portion of the mandrel, and spools thereon upon which the flexible elements composing the fabric are stored, rotatable devices for conducting and applying said flexible elements to the curved portion of the mandrel, said conducting and applying devices directed toward the center of curvature of 110 the curved portion of the mandrel, means for operatively connecting said conducting and applying devices with said reels, means for guiding the flexible elements from the spools on said reels to said conducting and applying devices.

9. In a machine for constructing an annular, tubular fabric, a flexible mandrel, a rigid guide and support upon which said mandrel travels, said guide having straight 120

- and curved portions, means for propelling the mandrel, a series of reels rotatable about the mandrel, spools upon said reels, concentric tubes axially arranged of the reels and 5 rotatable therewith about the straight portion of the mandrel, stationary tubes alternating and concentric with said rotatable tubes, driven gears rotatable about the curved portion of the mandrel, and directed 10 toward the axis of curvature of said mandrel, said gears rotatable upon the extremities of said stationary tubes, corresponding gears for operating the same and secured to said rotatable tubes, movable arms upon 15 said driven gears and conducting rollers on said arms, stationary rollers upon said driven gears, adjacent to said mandrel, and guiding means upon said reels and rotating tubes, said guiding means, conducting rollers, and stationary rollers adapted to conduct flexible elements from said spools and 20 apply the same upon said curved mandrel.
10. In a machine for constructing an annular, tubular fabric, a flexible, segmental 25 mandrel, a rigid support therefor, said support having a curved portion, means for propelling said mandrel on said support and over said curved portion, and devices rotatable about the curved portion of said 30 mandrel and support, for conducting flexible elements and for applying them to said mandrel, and means for rotating said rotatable devices.
11. A flexible mandrel comprising, a series 35 of segmental members hinged together at their outer edges, and a rigid support upon which said mandrel is longitudinally movable, said support provided with a curved portion.
40. 12. In a flexible mandrel, a series of segments of an annulus hinged together, and a rigid support therefor having a curved portion, and means for propelling said mandrel upon said rigid support.
45. 13. In a flexible mandrel, a series of segments hinged together at their outer edges, each segment formed in two portions, a rigid rail upon which said portions are mounted to inclose said rail between them, and means 50 for securing the portions of each segment together.

14. In combination, a flexible mandrel composed of segments of an annulus, means for hinging said segments together at their outer edges, a rigid rail having a curved 55 portion, said segments longitudinally movable upon said rail, each segment comprising two portions inclosing said rail between them, means for securing said portions of each segment together, a driving gear, and 60 engaging means on said segments for said driving gear.

15. In a flexible mandrel, a series of segmental members hinged together at their outer edges, each member composed of portions rigidly secured together, a rigid rail upon which said members are slidably mounted, the rail having a curved portion, 65 said rail inclosed between the two portions of each member, each member provided with an open slot in its inner edge, pins in each slot and a toothed wheel adapted to engage 70 said pins to propel said mandrel upon said rail.

16. In a device for conducting and for 75 applying flexible elements to a curved mandrel, the combination with the mandrel, of a rigid tube encircling the mandrel, a rotatable tube concentric with said rigid tube, a gear secured to the extremity of said rotatable tube, a gear rotatable upon said fixed tube and arranged at right angles to the axis 80 of the mandrel and directed toward the axis of curvature of said mandrel in the direction of a radius of the curve of said mandrel, 85 and driven by the gear upon said rotatable tube, arms radially movable upon said driven gear, guide rollers upon said movable arms, fixed rollers upon said driven gear adjacent to said mandrel, guiding rollers 90 upon said rotatable tube and means upon said rigid tube for engaging said arms to move the same, to maintain the flexible elements leading from the guide rollers upon said rotatable tube to the guide rollers on 95 said movable arms in a horizontal position.

In testimony whereof, I hereunto set my hand this 29th day of April, 1914.

LAWRENCE A. SUBERS.

In presence of—

ERNEST MOSMAN,

ADAM MEYER.
